(57) **CLAIM**

The ornamental design for an adjustable lounger, as shown and described.

DESCRIPTION

FIG. 1 is a perspective view of the adjustable lounger which is the subject of the present design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The dotted line portions in FIGS. 2, 3, 4, 5 and 7 are for the purpose of illustration only and do not form part of the claimed design.
